UNITED STATES PATENT OFFICE

ALBERT R. THOMPSON, OF SAN JOSE, CALIFORNIA, ASSIGNOR TO ANDERSON-BARN-GROVER MFG. CO., OF SAN JOSE, CALIFORNIA, A CORPORATION OF CALIFORNIA

CAN FEEDER FOR VERTICAL COOLERS

Application filed January 15, 1930. Serial No. 420,970.

My invention relates to the class of vertical coolers of the type disclosed in my previous Patents Nos. 1,651,912, December 6th, 1927, and 1,721,193, July 16th, 1929. It concerns 5 more particularly the feeding device by which the cans are supplied to the cooler.

On account of the general structure of the cooler, comprising a can chamber between spaced concentric walls, a helical, ascending 10 can track in said chamber, and a rapidly rotating reel of closely spaced pusher bars to roll the cans upon said track, it is essential that the cans, which are supplied through an opening in the side of the cooler, shall enter 15 between the bars not only with maximum timely precision but also under full control while so entering and until their control is completely assumed by said bars. I have found that it is better in some respects to pass 20 the cans on end through the feed turret and to tip them on to their sides into the cooling chamber, as shown in my earlier patent, instead of retaining them throughout the entire feed in a recumbent position, as in my later 25 patent above referred to. I have, accordingly, in the present case, while adopting the "tipping in" feed of the cans, improved the means therefor, not only for constructive simplicity, but also, and, chiefly, for effectiveness 30 in feeding and timing the entrance of the cans to the relatively narrow and fast moving spaces between the pusher bars of the cooler with a positiveness and control necessary to insure the continuity of the supply with no 35 tendency to obstruction or confusion.

The object of my present invention, therefore, is to provide a simple and effective can-feeder for vertical coolers of this type; and to this end it consists, briefly stated, in the 40 novel inclined can-feeding turret and its proximate relation to the cooler, as will be hereinafter fully described.

In the accompanying drawings, I have illustrated my can feeding device in its preferred form, though it is to be understood that changes may be made therein without departing from the spirit of the invention as defined by the claims hereunto appended.

Fig. 1 is a sectional side elevation of my 45 feeder, a portion of the cooler being shown,

and only the lower portion of the twisted feed chute 17 being included for want of space.

Fig. 1a is a view of the upper portion of the twisted feed chute 17, the lines $x-x$ in the two figures, indicating the respective coinciding ends of the chute sections. 55

Fig. 2 is a part sectional elevation at right angles to Fig. 1, the feed chute 17 being as before cut off for like reason.

Fig. 2a is a view of the cut off portion of the feed chute, which, as indicated by the lines $x-x$ immediately joins the portion shown in Fig. 2. 60

Fig. 2b is a view of the extremity section of said feed chute, the lines $y-y$ indicating the coinciding ends of the portions of Figs. 2a and 2b. 65

Fig. 3 is a plan view on the line 3-3 of Fig. 1.

Fig. 3a is a view, broken, of a portion of the feed chute 17, joining the portion shown in Fig. 3, as indicated by the lines $x-x$. 70

1 designates a portion of the annular treating chamber of the cooler to which the cans are to be fed. 2 are the concentric walls of the 75 chamber, and 3 are the rails forming an ascending helical track, as usual in this type of vertical cooler. The cans 4 roll on their sides along the track 3, and are propelled by a series of spaced pusher-bars 5. 6 is a ring 80 securing the lower ends of the bars 5, it being understood that their upper ends are joined by a similar member, not shown, to form a rigid reel. The outer wall of the chamber 1 is provided with an aperture 7 through which 85 the cans are introduced. 8 is a rotatable turret in immediate association with the aperture 7 of the cooler. The essential characteristic of this turret is its angular and proximate relation to the side of the cooler, it being inclined downwardly to and entering the feed aperture 7. The turret is rotatably mounted upon a spindle 9, which is carried in a suitable frame 10 secured to the lower portion of the cooler. The turret 8 is driven 90 from the reel ring 6 by a train of gears 11, 12, and 13 and a pair of bevel gears 14, one of the latter being secured to the bottom of the turret. The turret is formed with a peripheral 95 series of can-receiving and bodily-carrying 100

pockets 15 having closed bottoms but open outer sides and tops. 16, Fig. 3, is a fixed guard rail lying just outside of a portion of the turret periphery but terminating at the 5 feed aperture 7, whereby it does not obstruct the free communication of the pockets 15 of the turret with said feed aperture. The frame 10, which carries the turret, also carries a distorted or twisted feed chute 17, 10 which, at its upper end 17', is adapted to receive the cans rolling by gravity upon their sides, as shown in Fig. 3a, and at its lower end 17'' to turn the cans on their ends, as shown in Fig. 3, and to deliver them on end 15 to the pockets 15 of the turret. Beside this portion 17'' of the feed chute 17 there is a worm 18, which is adapted by engagement with the cans as they pass down the chute, to time them after the manner of such devices in 20 controlling a moving procession of cans. The worm 18 is driven, as shown in Fig. 2, from the gear train 11, 12, 13, through the gears 19, shaft 20, and pinions 21.

The operation of the feeder is as follows:—

25 The cans, from whatever source proceeding, roll down by gravity upon their sides in the initial portion 17' of the chute 17. As they arrive at the lower portion 17'' of said chute they are, due to the chute distortion or 30 twist, turned on end, and being engaged by the timing screw 18, they are delivered into the pockets 15 of the rotating turret 8. In these pockets, due to the inclination of the turret, they occupy an end-tilted position. As 35 the inclined turret rotates, the cans are retained in the pockets by the guard-rail 16. When they reach the lowest arc of revolution, at which time they are freed from the guard rail, they tip in by gravity through the cooler 40 opening 7 and fall into the cooler chamber 1 between the pusher bars 5 and lie upon the helical track in said chamber upon their sides. The angle at which the turret lies, with respect to the cooler, must necessarily be 45 one which will receive and carry the cans in an end-tilt beyond the angle of stability, so that when said cans cease to be restrained, they will, by gravity, tip out of the turret pockets 15. By properly calculating the degree of inclination, one can find the best angle 50 that will give the cans a tipping speed necessary to insure the maximum accurate delivery between the closely spaced and rapidly moving pusher bars 5 of the cooler.

55 Also it will be noted that in their construction, there is throughout the entire course of feeding, a minimum of sliding friction, since the cans are positively carried and supported within the pockets 15 of the turret 8, instead 60 of being slid along a stationary table by means of a rotating turret or star-wheel, as in my first patent. Therefore, although the cans are carried through the greater portion of their immediate approach to the cooler upon 65 their ends they are not subjected to sliding

pressure, but are positively bodily carried to their point of tipping entry into the cooler.

Another feature of importance herein lies in the positional relation of the inclined turret to the can-path in the cooler, which results in the positive control of the cans in their inclined position from their very reception in the turret to the moment when they are fully under the control of the pusher bars of the cooler path. This is well shown in Fig. 1, the 70 can 4, the tilted position of which is still maintained under turret control, is being positively introduced to the cooler path before said can starts to tip, the top end of the can being placed between the pusher bars and urged forward during the time of tipping to recumbent position, the bottom or outer side of the can being still under turret control and being propelled thereby during tipping and until full recumbency is reached. This, it will 75 be noted, is in contrast to the disclosure of my earlier patent above noted, wherein the can is dependent upon gravity tilting for its initial introduction to the cooler-path.

I claim:—

1. In apparatus of the class described, a can-way adapted for the rolling progression of cans; a reel of spaced bars adapted to advance the cans along said can-way; a turret associated therewith adapted for rotation in a plane inclined to the reel bars, and adapted to present the rounding surfaces of the cans to said bars at an angle thereto, said turret being adapted to control and advance the outer end of the can during the positioning of said cans.

2. In combination with a vertical cooler having a path adapted for the rolling progression of cans, a rotating reel of spaced pusher-bars adapted to roll the cans upon said path, and an inlet in its side communicating with said path and reel; a turret associated with said inlet, rotatable in a plane inclined to the pusher-bars and having pockets parallel with the turret axis adapting them to carry the cans end-tilted beyond the angle of stability, and to timely introduce them through said inlet and into the spaces between the pusher-bars, for gravity tipping to and rolling progression upon the cooler path, said pockets positively retaining control of the cans while tipping, adapted to insure their unimpeded introduction between and in timely accord with the rotation of said bars.

3. In combination with a vertical cooler having a path adapted for the rolling progression of cans, a rotating reel of spaced pusher-bars adapted to roll the cans upon said path, and an inlet in its side communicating with said path and reel; a turret associated with said inlet rotatable in a plane inclined to the pusher-bars and having pockets parallel with the turret axis and of a height less than the length of the cans, adapt-

ed to carry them end-tilted beyond the angle of stability with their upper ends projecting thereabove, said pockets being adapted to timely introduce the end-tilted cans through said inlet and into the spaces between the 5 pusher-bars for gravity tipping to and rolling progression upon the cooler path, said pockets during the tipping of the cans first yielding the upper ends thereof to the pusher bars, while temporarily retaining contact 10 with their lower ends in timely accord with the rotation of said bars.

4. In combination with a vertical cooler having a path adapted for the rolling progression of cans, a rotating reel of spaced 15 pusher-bars adapted to roll the cans upon said path, and an inlet in its side communicating with said path and reel; a turret associated with said inlet, rotatable in a plane inclined to the pusher bars, the lower periphery of said turret being adjacent said pusher-bars and traveling at substantially the same speed and adapted by said angular rotation 20 to place cans between said pusher-bars when said pusher-bars and turret periphery are 25 traveling in substantially a common direction.

5. In combination with a vertical cooler having a path adapted for the rolling progression of cans, a rotating reel of spaced 30 pusher-bars adapted to roll the cans upon said path, and an inlet in its side communicating with said path and reel; a turret associated with said inlet, rotatable in a plane inclined to the pusher-bars, the lower periphery of said turret being adjacent said pusher-bars and traveling at substantially the same speed and adapted by said angular rotation 35 to move cans toward the axis of the reel and between the pusher bars, the angle of the cans remaining constant during such advance.

In testimony whereof I have signed my name to this specification.

ALBERT R. THOMPSON.
